[57] CLAIM

The ornamental design for a container for prayer cards, as shown and described.

DESCRIPTION

FIG. 1 is a top, right front perspective view of a container for prayer cards showing my new design with the lid member in an opened position;

FIG. 2 is a front elevational view with the lid member in a closed position;

FIG. 3 is a rear elevational view of FIG. 2;

FIG. 4 is a top plan view of FIG. 2;

FIG. 5 is a right side elevational view of FIG. 1; and, FIG. 6 is a left side elevational view of FIG. 1.

The bottom of the article is plain and unornamented.

FIG. 1

FIG. 4

FIG. 2

FIG. 5
